UNITED STATES PATENT OFFICE.

EMIL HAEFELY, OF BASEL, SWITZERLAND, ASSIGNOR TO WESTINGHOUSE ELECTRIC AND MANUFACTURING COMPANY, A CORPORATION OF PENNSYLVANIA.

COIL-INSULATING DEVICE.

1,120,811.

Specification of Letters Patent. Patented Dec. 15, 1914.

Application filed July 10, 1909, Serial No. 507,003. Renewed August 1, 1912. Serial No. 712,771.

To all whom it may concern:

Be it known that I, EMIL HAEFELY, a citizen of the Republic of Switzerland, and a resident of Basel, in Switzerland, have invented a new and useful Improvement in Coil-Insulating Devices, of which the following is a specification.

My invention relates to the application of insulation to the coils of dynamo-electric machines and other types of electric apparatus, and it has for its object to provide a simple device by which a particularly desirable insulating wrapping or covering may be readily applied to coils of the class above indicated after they are bent into final form.

Coils which are applied to slotted cores of dynamo-electric machines to constitute distributed windings are usually bent or formed into final shape before they are assembled in the core slots and they are usually insulated by wrapping a number of layers of insulating tape or ribbon around them, either manually or by means of a taping machine. A considerable amount of time and labor is consumed in this process, particularly if the coils are relatively large.

According to my present invention, I provide a simple mechanism by means of which the insulating wrapping may be applied to the straight portions of a coil in a small part of the time consumed in the processes heretofore employed, and in such manner as to be held very firmly in contact with the coil itself, whereby it occupies a minimum amount of space and, when complete, constitutes a solid mass of insulation that is practically impervious to moisture and is capable of withstanding relatively high voltages.

It will be readily understood by those skilled in the art that the maximum insulation for a coil is required on the portions which lie in the core slots, and, as these portions are always straight, my improved mechanism may be employed to good advantage for providing the necessary insulation at these points even if usual methods are employed for insulating the remainder of the coil.

Figure 1 of the accompanying drawings is a perspective view of a device constructed in accordance with my invention, Figs. 2, 3 and 4 are diagrammatic views which illustrate the operation of the device of Fig. 1,

and Figs. 5 and 6 are, respectively, a partially sectional elevation and a front elevation of the structure shown in Fig. 1, several of the parts being broken away.

Referring to the drawings, the structure here shown comprises a tube or hollow rod 1 having a substantially rectangular cross section, brackets 2 which are secured thereto, an angle plate 3, brackets 4 secured to the angle plate, and spring boxes 5 which are interposed between the brackets 2 and 4 and are adapted to force the adjacent surfaces of the members 1 and 3 toward each other.

The tube or hollow rod 1 is preferably constructed of iron or some other heat-conducting material. The surface of the angle plate 3, which is adjacent to the tube 1, is preferably lined with a strip 6 of wood, although any other suitable material may be employed. Each of the brackets 2 and 4 is provided with a projection 8 which is adapted to register with a slot 9 in the top of each spring box 5, the arrangement of parts being such that the slots 9 constitute guide ways for maintaining the proper relation between the members 1 and 3 as they are adjusted toward and away from each other.

Each of the spring boxes 5 comprises a tubular outer casing 10 to which ends or heads 11 and 12 are secured, an inner rod or plunger 13 which is secured, at one end, to the bracket 2 and extends into the casing 10 through a hole in the head 11 and is provided with a head 14, and an intermediate tubular member 15 which is secured to the bracket 4 and extends through a hole in the end 12 into the tube 10 and is provided with a flange 16 at its free end.

A helical spring 17 is coiled about the intermediate tubular member 15 and is located between the flange 16 and the end member or head 12 and a helical spring 18 is coiled about the rod or plunger 13 and is located between the head 14 and the head 11. The springs are both under compression and serve to force the members 1 and 3 toward each other.

The method of utilizing the device is indicated in Figs. 2, 3 and 4, to which special reference may now be had. The pressure surface of the tube 1 is first heated by introducing a rod or bar 19 of iron or other suitable material which has been heated in any convenient manner. The straight por-

tion 20 of a coil is then clamped between the adjacent surfaces of the members 1 and 6 which are forcibly separated to admit the coil, a sheet of insulating fabric having 5 been wrapped once around the coil. The insulating device is then rotated as the coil is held stationary in such a direction as to wrap convolutions of insulating fabric upon the coil.

10 I prefer to employ a strip of insulating fabric which is constructed of paper treated with shellac or insulating varnish and coated with overlapping pieces of sheet mica, or some similar material which may be 15 softened upon the application of heat and fused to the adjacent layers. The tube or hollow rod 1 to which heat is applied by a bar 19 serves the purpose of softening the binder or shellac used in manufacturing the 20 insulating fabric, and, as the successive convolutions are wound on to the coil, the heat combined with the pressure exerted by the spring boxes 5 serves to cause the fabric to adhere to the coil and also produces, 25 when cold, a solid insulating covering which is not injured by adverse weather conditions and which is capable of sustaining very high voltages.

I claim as my invention:

- 30 1. A device for applying insulation to electric conductors comprising a pair of pressure members, and supporting brackets rigidly secured to the pressure members and yieldingly connected to each other.
- 35 2. A device for applying insulation to electric conductors comprising a hollow pressure tube of rectangular section, a pressure member coöperating therewith, a pair of supporting brackets rigidly secured to 40 the pressure members and yieldingly connected to each other, and means adapted to be disposed within the hollow pressure member for imparting heat thereto.
- 45 3. A device for applying insulation to electric conductors comprising a hollow pressure tube of rectangular section, a pressure member coöperating therewith, supporting brackets rigidly secured to the pressure members, and spring boxes connecting 50 the brackets together and comprising springs that force the pressure members toward each other.
- 55 4. A device for applying insulation to electric conductors comprising pressure members having plane engaging surfaces, supporting brackets for said pressure members, and springs and telescoping spring boxes interposed between said supporting brackets to force said pressure members 60 yieldingly toward each other and guide

them as they move toward and away from each other.

5. A device for applying insulation to electric conductors comprising a hollow pressure tube of rectangular section and 65 heat-conducting material, a second pressure member having a plane engaging surface coöperating therewith, brackets rigidly secured to the pressure members, and telescoping spring boxes connecting the brackets and serving as guides for the pressure members as they are moved toward and away from each other.

6. A device for applying insulation to electric conductors comprising a hollow 75 pressure tube having a plane surface, a second pressure member coöperating therewith, brackets rigidly secured to the pressure member, and spring boxes connecting the brackets for forcing the pressure members toward each other, each of said spring boxes comprising an outer tubular member, an intermediate tube secured to one bracket and extending into the outer tube, a rod or plunger secured to the opposite bracket and 80 extending into the intermediate tube, a helical spring coiled about the intermediate tube and compressed between the outer end thereof and one end of the outer tube, and a second helical spring coiled about the rod 85 or plunger and compressed between the outer end of the rod or plunger and the opposite end of the outer tube.

7. A device for applying insulation to electric conductors comprising a pair of 95 rigidly mounted pressure members having plane, normally parallel pressure surfaces and resilient means for subjecting the ends of the said members to substantially equal forces that tend to maintain the parallel 100 relation of the pressure surfaces as the device is revolved about the conductor to be insulated.

8. A device for applying insulation to electric conductors comprising a pair of 105 rigidly mounted pressure members having substantially parallel pressure surfaces, and resilient means for subjecting the ends of the said members to substantially equal forces that tend to maintain the parallel 110 relation of the pressure surfaces as the device is revolved about the conductor to be insulated.

In testimony whereof, I have hereunto subscribed my name this 8th day of July, 115 1909.

EMIL HAEFELY.
